UNITED STATES PATENT OFFICE

2,058,798

BOOSTER PUMP

Leslie E. Hughes, Wichita Falls, Tex.

Application November 2, 1933, Serial No. 696,430

1 Claim. (Cl. 103—194)

The invention appertains to liquid elevating mechanism and more particularly to pumps for use in oil fields for lifting oil and delivering it to a desired point.

5 The pump embodies two coacting units disposed the one above the other and connected by a pipe through which the oil, or other liquid, is discharged and through which the pump rod passes, the upper unit being of greater capacity than the lower unit to create and maintain a greater suction to cause oil to flow more freely into the well and insure the lower or regular pump working to predetermined capacity.

10 While the drawing illustrates a preferred embodiment of the invention, it is to be understood that in adapting the means to meet specific needs and requirements the design may be varied and changes in the minor details of construction may be resorted to within the scope of the invention as claimed without departing from the spirit thereof.

15 For a full understanding of the invention and the merits thereof, reference is to be had to the following description and the drawing hereto attached, in which:

20 Figure 1 is a sectional elevation illustrative of a pump embodying the invention.

Figure 2 is a view similar to Figure 1, parts being broken away.

25 Figure 3 is an enlarged sectional detail of the upper or booster pump unit and well casing.

Figure 4 is a sectional detail on the line 4—4 of Figure 2.

30 Corresponding and like parts are referred to in the following description and designated in the several views of the drawing by like reference characters.

35 The numeral 13 designates the usual casing of a deep well and 9 the head. Two pump units are located in the casing and are connected by a pipe 15. The upper pump unit boosts the action of the lower pump unit and comprises a cylinder 11 and piston 12. The lower pump unit includes a cylinder 17 and a piston 18. The upper unit is of greater capacity than the lower unit and augments the action of the latter to insure its working to maximum capacity. The piston 12 may be of any approved construction and is formed with a central opening 25 which connects with cages 22 and 26 fitted to the piston body. A valve 24 operates within the cage 22 to prevent return of the liquid. An imperforate pipe 15 connects the two cylinders of the pump

units and receives the pump rod 16 which connects the two pistons 12 and 18. The lower piston 18 is constructed substantially the same as the upper piston 12 and functions in a like manner. A foot or stand valve 19 is associated with the lower end of the pipe 15 to prevent return of the oil or other liquid pumped. A check valve 5 coacts with the outlet 8 in a manner well understood.

40 The pump units may occupy any relative position within the casing 13. The pistons 12 and 18 operate in unison and liquid drawn into the pipe 13 and cylinders 11 and 17 is retained by the stand valve 19. The lower pump unit functions in the accustomed manner. The upper pump unit, being of greater capacity, creates a suction in excess of the lower pump unit which reacts on the sands and slimes of an oil well to cause the oil to flow more freely into the pipe 13, thereby insuring the lower or regular pump working to full capacity. The polish rod 7, stuffing box 6, gland 4, fitting 8 and strainer 21, are well known parts of an oil well. The cylinder 11 may be closed by heads 10, 10a or 10b, according to its location. The head 10 is threaded into a flanged ring 28 supported upon an inner shoulder of the head 9. The top side of the flanged ring 28 is beveled and is engaged by screws 29 threaded into the head 9, thereby holding the ring 28 and parts carried thereby in place and comprising a gasket 27 interposed between the shoulder of the head 9 and the flange of the ring 28 so as to provide an air-tight seal for the upper portion of the casing 13.

45 Having thus described the invention, what I claim is:

50 A pump structure comprising a well casing, upper and lower pump cylinders located in the casing and in vertical alignment, means providing open communication between said cylinders, the upper cylinder having a discharge outlet, valved pistons in said cylinders and connected together, a foot valve controlling fluid admission to the lower cylinder, means closing and sealing the upper end of the casing, said upper and lower communicating cylinders being imperforate against air admission between the upper piston and the foot valve, and the upper cylinder and piston being of greater capacity than the lower cylinder and piston for creating a suction in the lower portion of the well casing.

LESLIE E. HUGHES.
